UNITED STATES PATENT OFFICE.

HERBERT H. CABLE, OF LOS ANGELES, CALIFORNIA.

ENGINE.

1,322,406.

Specification of Letters Patent. Patented Nov. 18, 1919.

Application filed January 14, 1919. Serial No. 271,018.

To all whom it may concern:

Be it known that I, HERBERT H. CABLE, a citizen of the United States, residing at Los Angeles, in the county of Los Angeles 5 and State of California, have invented new and useful Improvements in Engines, of which the following is a specification.

This invention relates to engines of the turbine or rotary type, the broad object of 10 the invention being to generate and utilize steam for driving the turbine elements or stators of the engine and at the same time utilize an explosive mixture which is ignited in the engine and delivered concurrently 15 with the steam into the casing in which the rotors operate, the combined fluids being directed against and through the rotors and stators and being exhausted through a common outlet.

20 A further object of the invention is to eliminate all valves in the turbine section of the engine, and eliminate to a considerable extent end thrust on the engine shaft and the drum on which the rotors are mounted.

25 The result is an engine of high efficiency, operating under a fluid or combination of fluids producing an elastic pressure against the working parts of the turbine section of the engine.

30 With the above and other objects in view, the invention consists in the construction, combination, and arrangement of parts, as herein described, illustrated and claimed.

In the accompanying drawings:—

35 Figure 1 is a vertical longitudinal section through the improved engine taken in line with the engine shaft, the latter being shown in elevation.

Fig. 2 is a face view of one of the stators.

40 Fig. 3 is a similar view of one of the rotors.

Fig. 4 is a detail view showing in cross section the formation of the coöperating stators and rotors.

45 Fig. 5 is an enlarged sectional view through the mixing chamber showing the controlling valves and the water inlet valve.

Referring to the drawings, 1 designates the engine shaft which is shown as mounted 50 in roller bearings 2 at different intervals in the length thereof and provided at one end with a coupling member 3 by means of which the engine shaft may be coupled to any mechanism to which power is to be 55 transmitted. The bearing 2 adjacent to the coupling 3 is supported by an upright por-

tion 4 of a frame 5, while the other bearings 2 are supported in casings 6 having connection with the heads 7 of the casing 8 of the turbine section of the engine. The 60 inner head 7 of the casing 8 is shown as forming a part of the frame 5, the cylindrical portion of the casing 8 being flanged and bolted to the frame 5 as shown at 9.

Within the casing 8 there are arranged 65 groups of stators 10, the groups progressively increasing in capacity toward the exhaust outlet 11 at the farther end of the casing 8, thus providing for the continued expansion of the fluid or fluids passing 70 through the casing 8. In conjunction with the stators 10 which are non-rotary and secured in any convenient way to the casing 8, I employ a corresponding number of rotors 12, all of said rotors being secured to 75 and encircling a hollow drum or shaft 13 which is of stepped formation as shown in Fig. 1, the same comprising the steps 14, 15 and 16 which are of progressively decreasing diameter as clearly shown. By reference to Fig. 2, it will be seen that each stator 80 is provided with V-shaped vanes 17 forming the V-shaped or arcuate passages therebetween, each stator also comprising a peripheral rim 18 having internal reaction shoulders or surfaces 19. By reference to Fig. 3, it will also be observed that each rotor 85 is provided with concentric series of V-shaped vanes 20, the vanes 20 being disposed reversely to the vanes 17 of the stators, the 90 expansion fluid acting directly on the vanes 20 and reacting upon the vanes 17 and surfaces 19 of the stators. The fluid or fluids entering, passing through, and leaving the casing 8 following the direction of the arrows and dotted lines in Fig. 1, wherein it will be observed that after the fluid acts upon one stator and rotor, moving outwardly from the center toward the periphery thereof, such fluid is directed again to 95 toward the center of the next adjacent rotor and stator through an L-shaped passage 21, there being such a passage between each couplet of rotors and stators as clearly shown in Fig. 1. The rotors are held upon 100 the drum or hollow shaft 13 by means of a lock nut 22 and said drum or hollow shaft is keyed or otherwise fastened to the engine shaft 1 as shown at 23.

Upon the frame 5, there is mounted an 110 engine frame or casting 24 which is water jacketed as shown at 25. The said frame or

casting comprises a mixing chamber 26 best shown in Fig. 5, said mixing chamber being adapted to be closed at the top by a puppet valve 27 and also adapted to be closed at the bottom by a similar valve 28, said valves having stems 29 and 30 working in suitable guides 31 and 32 and the valves being held yieldingly to their seats and returned thereto by means of springs 33. The valves 27 and 28 are simultaneously opened by means of a cam 34 on a cam shaft 35 suitably geared to the engine shaft 1. Located above the mixing chamber 26 is a water inlet chamber 36 which communicates with the mixing chamber 26 by means of a passage 37. Working in the chamber 36 is a rotary water inlet and measuring valve 38 having a single port 39 extending diametrically therethrough. Said valve 38 is of cylindrical formation and actuated by a shaft 40 which is suitably geared to the engine shaft and driven at the proper speed. A pipe 41 leads from an overhead water tank 42 to the chamber 36, the water from said chamber 36 to the mixing chamber 21 being controlled by the valve 38 which delivers the water in the proper quantity to said mixing chamber 26. The pipe 41 is equipped with a feed regulating valve 43. The valve 27 controls an outlet passage 44 leading off from the mixing chamber 26 and connected by a pipe 45 to a steam pressure tank 46 from which the steam is conducted into the casing 8 as will hereinafter appear. The valve 28 controls communication between the mixing chamber 26 and an explosion or combustion chamber 47 which is elongated as shown in Fig. 1 and provided adjacent to one end thereof with a mixture inlet 48, the inlet being controlled by an inlet valve 49 yieldingly held to its seat by means of a spring 50 and positively opened by means of a cam 51 on a cam shaft 52 suitably geared to the engine shaft. Between the inlet valve 49 and the valve 28, there is placed an ignition element such as a spark plug 51. At the other end of the combustion chamber 47 there is an exhaust chamber 52 controlled by an exhaust valve 53 yieldingly held against its seat by a spring 54 and positively operated by a cam 55 on a cam shaft 56 suitably geared to and actuated by the engine shaft. From the chamber 52, a pipe 57 extends to and through the adjacent head of the casing 8, the final portion of the pipe 57 being enlarged as shown at 58 to adapt it to receive an L-shaped steam nozzle 59 which receives the steam from the tank 46 and delivers the same into the enlarged portion 58 of the pipe 57, the mixture being then delivered to an annular jet pipe or manifold 59 which delivers the mixture through an annular series of jet openings against the initial set of vanes within the casing 8. The expand-

ing mixture then travels throughout the length of the entire casing impinging against the vanes of all of the stators and rotors until it escapes through the outlet or exhaust orifice 11.

From the foregoing description taken in connection with the accompanying drawings, the operation of the invention will now be understood. The explosive mixture under pressure is delivered to the combustion chamber 47 when the intake valve 49 is unseated. Said valve 49 is then seated and the explosive mixture ignited by the plug 44. At this time, the valve 28 is opened and the small quantity of water in the mixing chamber 26 is flashed into steam, and passes by the valve 27 and through the pipe 45 into the pressure 46 passing therefrom through the nozzle 59. The expanding mixture in the combustion chamber 47 passes the valve 53 which is opened at the proper moment and flows through the pipe 57, mixing with the steam beyond the nozzle 59, the combined mixture being then delivered into the casing 8 where it acts in the manner above described. As the mixture expands against the rotor and stator members, it moves outwardly in a general radial direction and thus eliminates most of the end thrust to which the rotors and their shaft are generally subjected in the ordinary construction of turbine engines. The result is a smoother working engine, and greater power efficiency. By thus combining an explosive mixture with steam, a highly elastic pressure is obtained rendering the engine flexible and powerful in operation and also economical in the consumption of liquid fuel. Gasolene or any other hydrocarbon oil may be used in conjunction with air as a combustible mixture. The water may, if desired, be drawn from the water jacket 25 so that water having a fairly high temperature may be used for delivery to the mixing chamber 26, thereby facilitating the generation of steam in said mixing chamber.

It will be understood that the engine as a whole is susceptible to changes in the form, proportion and minor details of construction which may accordingly be resorted to without departing from the principle or sacrificing any of the advantages of the invention.

I claim:—

1. In an engine of the class described, the combination of a rotary casing, an engine shaft extending centrally therethrough, a plurality of stators in said casing, a plurality of rotors in co-operative relation to said stators and connected fixedly with said shaft, a combustion chamber arranged exteriorly of said rotor casing, a mixing chamber, a valve controlling communication between said mixing chamber and combustion chamber, an intake valve for delivering an explosive mixture under pressure to said

- combustion chamber, ignition means, an exhaust connection between said combustion chamber and rotor casing, an exhaust valve controlling the last named connection, a 5 valve controlled water supply for said mixing chamber, and valve controlled connecting means between said mixing chamber and said rotor casing.
2. In an engine of the class described, the 10 combination of a rotor casing, an engine shaft extending centrally therethrough, a plurality of stators in said casing, a plurality of rotors in coöperative relation to said stators, and connected fixedly with said 15 shaft, a combustion chamber arranged exteriorly of said rotor casing, a mixing chamber, a valve controlling communication between said mixing chamber and combustion chamber, an intake valve for delivering 20 an explosive mixture under pressure to said combustion chamber, ignition means, an exhaust connection between said combustion chamber and rotor casing, an exhaust valve controlling the last named connection, a 25 valve controlled water supply for said mixing chamber, and valve controlled connecting means between said mixing chamber and said rotor casing, the last named connecting means embodying a steam nozzle which dis- 30 charges into said exhaust connection adjacent to the point of delivery of the latter.
3. In an engine of the class described, the 35 combination of a rotor casing, an engine shaft extending centrally therethrough, a plurality of stators in said casing, a plurality of rotors in coöperative relation to said stators, and connected fixedly with said shaft, a combustion chamber arranged exteriorly of said rotor casing, a mixing chamber, a valve controlling communication between 40 said mixing chamber and combustion chamber, an intake valve for delivering an explosive mixture under pressure to said combustion chamber, ignition means, an exhaust connection between said combustion chamber and rotor casing, an exhaust valve controlling the last named connection, a 45 valve controlled water supply for said mixing chamber, valve controlled connecting means between said mixing chamber and said rotor casing, the last named connecting means embodying a steam nozzle which dis- 50 charges into said exhaust connection adjacent to the point of delivery of the latter, and an annular manifold within said rotor casing into which the steam and expanding mixture are delivered, said manifold having a plurality of jet openings.
4. In an engine of the class described, the 55 combination of a rotor casing, a rotor there- 60
- in, a mixing chamber, a combustion chamber, a positively operated valve controlling communication between said mixing chamber and combustion chamber, means for forcing an explosive mixture under pressure into said combustion chamber, ignition means, an exhaust connection between said combustion chamber and the rotor casing, a positively operated valve controlling communication between said combustion chamber and exhaust connection, a water supply in communication with said mixing chamber, a steam outlet connection for said mixing chamber arranged to discharge into said rotor casing, a positively operated valve controlling said steam outlet connection. 65
5. In an engine of the class described, the combination of a rotor casing, a rotor there- 70 in, a mixing chamber, a combustion chamber, a positively operated valve controlling communication between said mixing chamber and combustion chamber, means for forcing an explosive mixture under pressure into said combustion chamber, ignition means, an exhaust connection between said combustion chamber and the rotor casing, a positively operated valve controlling communication between said combustion chamber and exhaust connection, a water supply in communication with said mixing chamber, a steam outlet connection for said mixing chamber arranged to discharge into said rotor casing, a positively operated valve controlling said steam outlet connection, and a measuring valve controlling said water supply. 75
6. In an engine of the class described, the combination of a rotor casing, a rotor there- 80 in, a mixing chamber, a combustion chamber, a positively operated valve controlling communication between said mixing chamber and combustion chamber, means for forcing an explosive mixture under pressure into said combustion chamber, ignition means, an exhaust connection between said combustion chamber and the rotor casing, a positively operated valve controlling communication between said combustion chamber and exhaust connection, a water supply in communication with said mixing chamber, a steam outlet connection for said mixing chamber arranged to discharge into said rotor casing, a positively operated valve controlling said steam outlet connection, and a measuring valve controlling said water supply. 85
6. In an engine of the class described, the combination of a rotor casing, a rotor there- 90 in, a mixing chamber, a combustion chamber, a positively operated valve controlling communication between said mixing chamber and combustion chamber, means for forcing an explosive mixture under pressure into said combustion chamber, ignition means, an exhaust connection between said combustion chamber and the rotor casing, a positively operated valve controlling communication between said combustion chamber and exhaust connection, a water supply in communication with said mixing chamber, a steam outlet connection for said mixing chamber arranged to discharge into said rotor casing, a positively operated valve controlling said steam outlet connection, and a measuring valve controlling said water supply. 95
6. In an engine of the class described, the combination of a rotor casing, a rotor there- 100 in, a mixing chamber, a combustion chamber, a positively operated valve controlling communication between said mixing chamber and combustion chamber, means for forcing an explosive mixture under pressure into said combustion chamber, ignition means, an exhaust connection between said combustion chamber and the rotor casing, a positively operated valve controlling communication between said combustion chamber and exhaust connection, a water supply in communication with said mixing chamber, a steam outlet connection for said mixing chamber arranged to discharge into said rotor casing, a positively operated valve controlling said steam outlet connection, and a measuring valve controlling said water supply. 105
6. In an engine of the class described, the combination of a rotor casing, a rotor there- 110 in, a mixing chamber, a combustion chamber, a positively operated valve controlling communication between said mixing chamber and combustion chamber, means for forcing an explosive mixture under pressure into said combustion chamber, ignition means, an exhaust connection between said combustion chamber and the rotor casing, a positively operated valve controlling communication between said combustion chamber and exhaust connection, a water supply in communication with said mixing chamber, a steam outlet connection for said mixing chamber arranged to discharge into said rotor casing, a positively operated valve controlling said steam outlet connection, a measuring valve controlling said water supply, and a feed regulating valve controlling said water supply. 115

In testimony whereof I affix my signature.

HERBERT H. CABLE.
